UNITED STATES PATENT OFFICE

2,484,232

VALVE STRUCTURE FOR AERATING
BOTTLES OR THE LIKEWilliam B. Kochner, St. Louis, Mo., assignor, by
mesne assignments, to Knapp-Monarch Com-
pany, St. Louis, Mo., a corporation of Delaware

Application November 8, 1944, Serial No. 562,554

3 Claims. (Cl. 251—134)

1

My present invention relates to a valve structure for an aerating bottle or the like in which liquid, such as cream or the like, is adapted to be aerated or similarly treated although the invention may be applied to other uses such as in connection with siphon bottles.

One object of my invention is to provide an aerator having a control valve structure of simple, durable and inexpensive construction.

Another object is to provide the control valve structure in the form of an assembly which may be readily removed from the aerator and taken apart to permit ready access to all parts thereof exposed to liquid from the vase, for easy, quick and thorough cleaning thereof.

Another object is to provide a valve assembly which when taken apart permits ready cleaning of the passageways leading to and from the valve, which passageways are short and direct for this purpose.

A further object is to provide a valve structure which may be readily operated by depressing a hand lever after the aerator has been filled with liquid and the liquid aerated, the operating lever being readily removable during the disassembly of the valve parts with a minimum of effort on the part of the user.

With these and other objects in view, my invention consists in the construction, arrangement and combination of the various parts of my device whereby the objects contemplated are attained, as hereinafter more fully set forth, pointed out in my claims and illustrated in the accompanying drawings, wherein:

Figure 1 is a perspective view of an aerator or the like including a valve embodying my invention.

Figure 2 is an enlarged, vertical sectional view through the head of the aerator showing the valve in closed position.

Figure 3 is a similar view showing the valve open.

Figure 4 is a horizontal sectional view on the line 4—4 of Figure 2, and

Figure 5 is an exploded sectional view with some of the valve parts in side elevation showing their separation for cleaning purposes.

On the accompanying drawings I have used the reference numeral 10 to indicate a vase adapted to receive liquid such as cream or an ice cream mix. Detachably mounted on the vase 10 is a vase head 12. The vase head 12 is provided with screw threads 14 adapted to coact with threads of the vase 10 in the usual manner so that the head may

2

be attached and detached relative to the vase as desired.

In the vase head 12 I provide a vertical passageway 16 and a lateral passageway 18. The passageway 16 terminates in a valve seat 20 and the passageway 18 leads to a decorating nozzle 22 screwed into the vase head 12.

The vase head has a pair of bores 24 and 26 aligned with the passageway 16 and of different sizes with the transition from one size to the other forming a shoulder 28. A combined gasket and valve plug element A is provided having a valve plug portion 30, a cylindrical diaphragm portion 32 and a gasket ring portion 34. The element A may be made of rubber or the like and the gasket ring 34 thereof seats on the shoulder 28. For seating the gasket ring on the shoulder, I provide a sleeve 36 having an inturned flange 38 at its lower end and an out-turned flange 40 at its upper end. The flange 38 is adapted to contact the gasket ring 34 and a closure nut 42 is adapted to contact the flange 40. The nut 42 is knob-like in character and is threaded onto the upper end of the valve head 12, indicated at 44, which end is threaded for this purpose. The upper end 44 has a notch 46 therein with which a displaced portion 48 of the sleeve 36 coacts for preventing rotation of the sleeve relative to the head.

A valve stem S is provided having a head 50 removably imbedded in the valve plug portion 30 of the element A, and an enlargement 52 between its lower and upper ends. A spring 54 is mounted between the enlargement 52 and the closure nut 42 for normally seating the valve plug 30 on the valve seat 20.

The sleeve 36 is slotted at one side, as indicated at 56, and the head 12 has a slot 58 aligned therewith. The head also has a pivotal projection 60, and a handle H is provided with a depression 62 for pivotal coaction therewith. The handle H has an opening 64 therein through which the stem S loosely extends and on opposite sides has a pair of projections 66 adapted to contact the lower edge of the enlargement 52.

Practical operation

In the operation of my valve structure the vase 10 having been filled with cream or the like and the cream aerated by the introduction of gas under pressure, the apparatus can be used for dispensing the aerated cream by tipping it to an inverted position with the nozzle 22 pointing approximately downward and the valve may be opened from the position of Figure 2 to the position of Figure 3 by depressing the handle H. The

discharge of aerated cream can be controlled by the degree of depression of the handle.

When it is desirable to clean the valve structure this may be readily done by unscrewing the knob 42 so that all the parts shown in Figure 5 can be withdrawn from the head 12. The handle H is disconnected from the stem S after the head 50 of the stem has been pulled out of the element A. Each of the parts may then be individually washed and the passageways 16 and 18 cleaned out with a brush or the like as may also the bore portions 24 and 26 of the head 12. The device may thereby readily be kept in a sanitary condition and after cleaning the valve may be reassembled with a minimum of effort on the part of the operator.

Some changes may be made in the construction and arrangement of the parts of my device without departing from the real spirit and purpose of my invention, and it is my intention to cover by my claims any modified forms of structure or use of mechanical equivalents which may be reasonably included within their scope without sacrificing any of the advantages thereof.

I claim as my invention.

1. For use with a body member having a passageway therethrough, a valve seat interposed in said passageway, a bore aligned with said valve seat, a shoulder and a second bore, said shoulder being between the first and second bores; a valve and operating assembly comprising a combined valve plug and gasket element having a plug at one end, a gasket ring at its other end and a flexible wall connecting said ends together, a valve stem for said plug end of said element, said valve stem having an enlargement, a sleeve positioned in said second bore, means removably positioned on said body member to engage said sleeve and cause it to engage said gasket ring between the inner end of the sleeve and said shoulder, a spring interposed between said means and said valve stem to normally seat said valve plug on said valve seat, a hand lever member having a cupped end interposed between said enlargement and said element to retract said stem and valve plug, one of said members having a notch and the other member having a pivot projection received in said notch, said cupped end receiving said enlargement to normally retain said pivot projection in said notch.

2. For use with a body member having a passageway therethrough, a valve seat interposed in said passageway, a bore aligned with said valve seat, a second bore forming a continuation of said first bore and a shoulder between said bores; a valve and operating assembly comprising a combined valve plug and gasket element having a plug at one end, a gasket ring at its other end,

and a flexible tubular wall connecting said ends together, a sleeve for engaging said gasket ring, a closure nut threaded on said body member and engaging said sleeve to effect abutment of said gasket ring against said shoulder, slots in one side of said body member and said sleeve, said slots being open at the top, an enlargement on said stem within said sleeve, a spring interposed between said closure element and said enlargement, and a lever pivoted on said body member adjacent said sleeve, having a portion pivoted against said enlargement for retracting said valve stem and plug when said handle is depressed, and having a portion extended thru said slots, said closure nut closing the open ends of said slots and retaining said handle therein.

3. For use with a body member having a passageway therethrough, a valve seat interposed in said passageway, a bore aligned with said valve seat, a second bore forming a continuation of said first bore and a shoulder between said bores; a valve and operating assembly comprising a combined valve plug and gasket element having a plug at one end, a gasket ring at its other end, and a flexible tubular wall connecting said ends together, a sleeve for engaging said gasket ring, a closure nut threaded in relation to said body member and engaging said sleeve to effect abutment of said gasket ring against said shoulder, slots in one side of said body member and said sleeve, said slots being open at the top, an enlargement on said stem within said sleeve, a spring interposed between said closure element and said enlargement, and a hand lever member having a cupped end interposed between said enlargement and said combined valve plug and gasket element to retract said stem for opening said valve, one of said members having a notch and the other member having a pivot projection received therein, said cupped end receiving said enlargement to normally retain said pivot projection in said notch.
